UNITED STATES PATENT OFFICE.

JAMES KYTE ROBERTSON AND SAMUEL DUDERDEN, OF WHITEHALL, BRISTOL,
ENGLAND.

WEB-FEEDING MECHANISM.

Application filed December 6, 1923; Serial No. 678,857, and in Great Britain December 11, 1922.

This invention relates to a device or mechanism for automatically adjusting and controlling the running of a previously-printed, or recurrently and spacedly-marked and re-wound, web of material, such as a reel of paper or cardboard, whereby continuous accurate register of the recurring imprints or marks relative to the operation of subsequent mechanism, such as stamping, 10 creasing, folding, severing or additional imprint-placing mechanism is obtained.

It is found, when a continuous web of material, such as paper, is printed or spacedly marked and rewound into reel form, owing to the flexibility or elasticity of the material, combined with the varying tension exerted thereon to suitably rewind same, the relative position of the recurring marks or imprints vary irregularly from their original spaced positions, and when such previously printed or marked reel of paper is subsequently used in automatic machines (such as, for instance, a continuous-action paper bag-making machine) the position of the imprint or mark is continuously and irregularly varying from its required position relative to the folding mechanism of such bag-making machine.

It is also extremely difficult, owing to known and unavoidable discrepancies due to workmanship, material and wear, wherever absolute register is required, to so adjust or time a supplementary automatic machine to operate accurately in required step or pitch 35 with the original printing or marking machine.

It is the object of this invention to provide means for automatically keeping the imprints or spaced marks (which, owing to the causes before mentioned, have become slightly and irregularly displaced from their original spaced pitch or step during the rewinding process) consecutively in register with definite timed operations of the bag-making or other machine.

To this end, and to enable us to arrive at our objective, it is necessary that one or more perforations be made in the web of paper or other material in a suitable position relative to each consecutive imprint or mark, and such perforation must be made in the web of material at the same time, or during the process of, the imprint or mark being placed thereon, and always previous 50 to the rewinding of such web into reel form.

According to this invention we provide in mechanism in which a pin on a roller engages holes in a web of paper or other material, means for ensuring that the pins will enter the holes whether or not the holes occur at exactly regular intervals, and means for taking the tension off the section of the web in which the holes are engaged by pins, so that tearing is prevented, said means comprising a pair of rollers adapted to grip the web, one of which is provided with pins, and means whereby at intervals the pair of rollers does not grip the web, a second roller or pair of rollers which is adapted to feed the web to the pin roller at a slightly faster rate than the web is passed by the pin roller, means being provided whereby at intervals the second pair of rollers does not grip the web; and a third roller or pair of rollers adapted to grip the web when the first mentioned pair of rollers does not grip in order to take up the tension produced by any other operations.

In one example showing the manner in which our device or mechanism may be constructed and operated we proceed to describe and explain same working in conjunction with a well known type of continuous-action paper bag-making machine, as illustrated in the accompanying drawing which is a diagrammatic side elevation, but it must be clearly understood that we do not confine or limit ourselves to such application, as the invention is obviously applicable to a very wide range and variety of automatic paper and cardboard, and similar material, handling machinery.

The device or mechanism is placed in any suitable position along the path of travel of the paper web *a* from its reel *b* to the draw rollers *c* of the bag-making machine and for convenience may be placed just previous to the commencement of the formation of the paper web into its required tube form and the device must be suitably and definitely driven from some shaft on the bag-making machine whereby the imprint-adjusting device may be driven or operated in step or pitch with the folding mechanism of the bag-making machine. In the example, the driving shaft is indicated at *d*, and this shaft drives the roller *e* and the rollers *f*, *g*, *h* and *i* which are geared thereto. The shaft *d* is positively driven from some suitable shaft of the bag-making machine.

The imprint-adjusting mechanism comprises a number of rollers *e h* with less than a complete surface tread working in conjunction with other complete tread rollers *f g* arranged to draw the web of paper *a* from the reel *b* in such a manner as to ensure that the projecting tapered pins *j* carried by one *g* of the rollers *g h* shall always enter the holes or perforations previously made in the web at the time the imprint was made thereon, which object is attained by drawing the web of paper by a pair of rollers *g h* one of which carries the pins *j* intended to enter the perforations, and feeding the web of paper at a slightly accelerated rate of feed towards such pins by the rollers *e f* so as to ensure the pins having a sufficient surplus supply of paper to adjust themselves accurately in the perforations without strain or tension and passing such adjusted paper along by means of the pins through the cut away portion of the tread of one *h* of the first mentioned pair of rollers *g h* after passing the centre of which the tread immediately follows and again grips the paper web, the feed acceleration roller *e* then ceases to act for the cut away portion of its surface, thus enabling whatever surplus feed of paper remains to be immediately absorbed. It is also necessary to provide a further segmental gripping roller *i* arranged to control the paper web during the time the pins *j* are carrying the adjusted web into the grip of the draw rollers *g h* of the device, so as to prevent any strain or tension from the draw rollers *c* of the bag-making machine acting upon the leading portion of the web of paper, and thereby tearing or distorting the adjustment or register already obtained, until the cut away portion of the draw roller *h* has passed and the tread again grips the web immediately following the passing of the adjusting pins *j*. Thus it will be clear that we employ equivalent to three pairs of rollers, each pair acting or gripping the web of paper for a portion of the revolution only, but one or other pair of rollers has successive control of the paper web during its passage through the adjusting device or mechanism. The segmental excess feed roller *e* is slightly larger in diameter than the other two segmental rollers *h i* which latter are of a circumference approximately equivalent to the length of paper between each successive point of imprint or perforation originally made on the web of paper. It may be convenient to arrange the roller *g* carrying the adjusting pins *j* to be of a circumference equal to a multiple of the circumference of the two segmental rollers *h i* in which case we find it convenient to arrange the two segmental rollers of equal circumference to operate in unison with the large pin carrying roller *g* and thus save the equivalent of a separate roller, the pin-carrying roller and

the two segmental rollers thus acting equivalent to two separate pairs of rollers.

It must be understood that in order to achieve our object it is necessary to so adjust the draw rollers *c* of the bag-making machine that they (if otherwise uncontrolled) would draw a slightly longer length of paper web than the imprint-adjusting device (including whatever slight additional length of web may be passed in the adjustment process) supplies to them, this slight restriction of supply to the bag-making machine serving the double purpose of providing sufficient tension or "pull" action between the adjusting device and the bag-making machine draw rollers to allow the paper web to be satisfactorily formed into the required tube form and also ensures the reliable absorption of all the paper supplied by the adjusting device which, within narrow limits, is somewhat of an irregular length. We utilize the facts that the paper is flexible or elastic and also that it can readily be made to slip slightly in the draw rollers of the bag-making machine without actual damage to the web of paper, and the utilization of these characteristics in conjunction with the mechanism or device described enables us to obtain continuous and accurate adjustment of the imprint relative to the bag-feeding mechanism of the bag-making machine.

Although segmental rollers are described, it is clearly understood that the same results of releasing the grip on the paper could be obtained by lifting the rollers apart at predetermined times by means of cams or other mechanism.

Or other intermittent gripping and releasing devices adapted to operate similarly may be provided, and means may be provided for varying the interval of grip and release to provide for different lengths of product.

From the foregoing it will be seen that by our invention the material is drawn through the device or mechanism by, and in the course of, subsequent operations, that is to say, the material is fed under tension or "pull" action effected by the mechanism performing subsequent operations.

What we claim and desire to secure by Letters Patent is:—

1. In, or in connection with, a paper bag-making or other machine and its mechanism for automatically adjusting and controlling the running of a previously-printed or recurrently- and spacedly-marked and rewound web of material by means of tapered pins which are mounted on one of a pair of rollers and adapted to fit into, and thereby regulate the position of, holes or apertures previously spaced equidistantly in the web of material, a device for intermittently gripping the web of material between the said

mechanism and the origin of the said pull to create a web slack, thereby permanently maintaining the web of material in the mechanism in an unstrained condition, draw rolls tending to maintain a constant tension on said rolls first mentioned and intermittently operating means located between said drawing rolls and said rolls first mentioned for releasing the tension of the draw rolls

10 on the rolls first mentioned.

2. In, or in connection with, a paper bag-making or other machine and its mechanism for automatically adjusting and controlling the running of a previously-printed or recurrently- and spacedly-marked and rewound web of material by means of tapered pins which are mounted on one of a pair of rollers and adapted to fit into, and thereby regulate the position of, holes or apertures previously spaced equidistantly in the web of material having a surplus of material adja-

cent to, and loose between, the said rollers at the point when the pins enter the said apertures, the provision of a pair of rollers having on the periphery of one a cam whose surface is adapted to bear upon the material passing between, and throughout that period during which, the pins enter and adjust the position of the holes in the material, and during which the material is loose between the rollers upon which the pins are mounted, draw rolls tending to maintain a constant tension on said rolls first mentioned and intermittently operating means located between said drawing rolls and said rolls first mentioned for releasing the tension of the draw rolls on the rolls first mentioned.

In testimony whereof, we affix our signatures.

JAMES KYTE ROBERTSON.
SAMUEL DUERDEN.
